CLAIM

We claim the ornamental design for an electric power adapter, as shown.

DESCRIPTION

FIG. 1 is a front side view of the electric power adapter;

FIG. 2 is a rear side view thereof;

FIG. 3 is a right side view thereof;

FIG. 4 is a left side view thereof;

FIG. 5 is a top side view thereof;

FIG. 6 is a bottom side view thereof;

FIG. 7 is a front, right, bottom isometric view thereof; and,

FIG. 8 is a back, right, top isometric view thereof.

The broken lines in the drawings are for illustrative purposes only and form no part of the claimed design.
